INVENTOR.

Franklin A. Smith Jr.

UNITED STATES PATENT OFFICE.

FRANKLIN A. SMITH, JR., OF PROVIDENCE, RHODE ISLAND.

BUTTON-FASTENER.

SPECIFICATION forming part of Letters Patent No. 295,447, dated March 18, 1884.

Application filed January 23, 1884. (No model.)

To all whom it may concern:

Be it known that I, FRANKLIN A. SMITH, Jr., a citizen of the United States, residing at Providence, in the county of Providence and State of Rhode Island, have invented certain new and useful Improvements in Button-Fasteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improvement in that class of devices for securing buttons to fabric by means of which a button can be readily attached or detached without injury to the fastener, and without the aid of a setting-instrument.

To this end my invention consists, practically, of a hook-formed metallic fastener consisting of a head or retaining portion, from the upper surface of which projects a curved hook and a washer or disk formed of leather, leather-board, pulp, or other non-metallic substance, having a central opening counterbored on one side of said washer; also, a recess or indentation on the outer edge of the washer, all 30 as will be more clearly described hereinafter.

In the accompanying drawings, Figure 1 is a side and bottom view of the metallic hook; Fig. 2, a side and bottom view of my improved washer. Fig. 3 represents the complete device ready for attachment. Fig. 4 represents my improved fastener with button attached to fabric. Figs. 5 and 6 are views of modifications of hook and washer.

Referring to the drawings, A is a headed nail or tack bent into shape, substantially like that shown in Fig. 1, consisting of the head a, curved loop b, and point c. The head a and point c are nearly on a line with each other, with the point c some distance from the side 45 of the head a, as shown in Fig. 1. This hook constitutes the first feature of my invention. The other feature consists of the washer B, which is formed of the above-mentioned non-metallic substances, but more preferably 50 leather, and is provided with the central opening, e, which is counterbored on the outer sur-

face of the washer, as shown at d in Fig. 2. The outer surface of the washer is also rounded to present a smooth finished appearance. It is also provided on its edge with a recess or indentation, f, into which the point c of the fastening-hook A extends when the two parts are united, the head a of the hook A resting in the counterbored portion d, which is of the same form or configuration as the head a. 55 60

In the manufacture of my improved fastener the nail or tack may be first passed through the washer straight and secured thereto, and afterward bent into form; but I prefer to make them separate and then unite them, in which case the washer is first formed, as described, and the nail or tack, after having been bent into shape, is passed through the washer from the rounded side, and carried around until the point c is curved over into the recess or indentation f, and the head a reaches the counterbored portion d of the central opening, e, of the washer, into which it is pressed, thus securely fastening the hook and washer together, the head a forming a smooth surface 75 with the rounded portion of the washer, thus forming the complete device shown in Fig. 3.

The operation of attaching a button to fabric is as follows: The eye of a button is first passed through a hole previously made in the fabric. 80 The edges a³ of the recess portion of the washer and then placed against the under surface of the fabric, with the recess in the washer circling the protruding button-eye, which position brings the point c of the hook portion A directly opposite the opening in the button-eye, when the hook portion can be readily passed through the button-eye until the inner surface of the washer lies snugly against the under surface of the fabric, thus securing the 85 button in position, with the button-eye resting in the hook portion b, as fully shown in Fig. 4. The hook portion b, being practically embedded lengthwise of the opening in the fabric, prevents it from being turned around in use, while the point c of the hook, extending below the inner surface of the washer, prevents the possibility of the button becoming 90 detached by unhooking. 95 100

The metallic hook A of itself forms a substantial fastening for attaching buttons to thick leather and the like. Independent of the

washer, but for general use as a fastener for all grades of material, the combined hook and washer offers a greater amount of resistance to any strain which may be brought to bear on the button.

5 The modifications shown in Figs. 5 and 6 are substantially the equivalent of the above-described hook and washer, the hook shown in Fig. 5 being cut from sheet metal of the same form as the hook shown in Fig. 1, without any bending or further manipulation, the washer shown in Fig. 6 being the same as that shown in Fig. 2, with the exception of the central opening, *e*, and counterbored portion *d*, which 10 is formed to correspond with the shape of the cut head *a'* shown in Fig. 5, the final result being the same in both cases. When the hook and washer are united they form the complete fastener shown in Fig. 3.

15 20 It will be observed that the washer, being formed of leather or other non-metallic substances, presents a smooth finished appearance on the under surface of a garment, and the outer edges are not as liable to cut or chafe 25 the fabric, as is the difficulty with a metal washer. The washer is also adapted to be stained or colored to correspond with the color of the fabric to which it may be attached.

I am aware that metal washers have heretofore been used in combination with bent hooks 30 and pins and staples; but I am not aware of a washer ever having been made before like the one herein described, or a hook of the configuration of the metal one here shown and described.

35 Having described my invention, what I claim as new, and desire to secure by Letters Patent, is—

1. The metallic fastener *A*, having head portion *a*, curved loop *b*, and point *c*, arranged 40 and adapted for use as described.

2. In a button-fastener, the metallic hook *A*, having head *a*, loop *b*, point *c*, and the non-metallic washer *B*, provided with central opening *e*, counterbored portion *d*, and recess 45 *f*, combined, substantially as shown and described.

In testimony whereof I affix my signature in the presence of two witnesses.

FRANKLIN A. SMITH, JR.
